DE VER H. WARNER, OF BRIDGEPORT, CONNECTICUT, ASSIGNOR TO THE WARNER BROTHERS COMPANY, OF BRIDGEPORT, CONNECTICUT, A CORPORATION OF CONNECTICUT.

STOCKING-SUPPORTER.

SPECIFICATION forming part of Letters Patent No. 713,184, dated November 11, 1902.

Application filed May 21, 1902. Serial No. 108,295. (No model.)

To all whom it may concern:

Be it known that I, DE VER H. WARNER, a citizen of the United States, and a resident of Bridgeport, Fairfield county, Connecticut, 5 have invented certain new and useful Improvements in Stocking-Supporters, of which the following is a specification.

My invention relates to a stocking-supporter by means of which the stockings are 10 supported from the lower portion of the corset or other garment. Heretofore in devices of this character which have been attached directly to the corset by safety-pins, clasps, or the like the tendency has been to tear the 15 fabric of the corset and to pull it out of place. By reason of this tearing and displacement, which results in lasting injury to the corset, the pin or clasp is loosened and fails to hold. The consequence has been that such attaching devices, simple in themselves, have been 20 discarded for more elaborate and complicated structures, which have assured greater safety and confidence.

The object of the present invention is to 25 provide a means which while not dispensing with safety-pins or clasps as a means of attachment obviates the objectionable features attendant upon their use.

My invention will be understood by reference to the accompanying drawings, in 30 which—

35 Similar letters of reference indicate similar parts in the several views.

Referring to the drawings, A and A' designate the suspension elastics or tapes of the supporter. The tapes may be made of any 40 suitable material and are adjustable in length by means of the slides a and a', respectively. To the lower ends of the tapes are attached the loops a² a³ and the webbing a⁴ a⁵. To the last named the buttons a⁶ and a⁷ are attached. 45 The form of the supporter illustrated and so far described is well known and is no part of my present invention. Attached to the upper end of said tapes or to a suspension-ring, as B, through which the tapes may also be passed, and extending upwardly therefrom is 50 a tab C, made, preferably, of a reticulated or loosely-woven fabric. This tab may have a single extension, as shown in Fig. 2, or it may be doubled to provide two extensions c and c', as shown in Fig. 1. In the latter form the 55 lower edge of the corset falls between the two extensions—that is, the extension c rests upon the front, and extension c' upon the under, side of the corset. The tab may have its edge bound with tape to prevent fraying. When 60 attached to a corset or other garment by the pin D, the prong d passes readily through the reticulated or loosely-woven fabric composing the tab without injuring the same, and the tendency to tearing of the corset is removed 65 or lessened, inasmuch as the strain is distributed from the closely-woven garment fabric to the loosely-woven tab material. My invention thus provides a supporter easy of application and obviating the disadvantages at- 70 tendant upon pinning the supporter directly to the corset or other garment.

What I claim as my invention, and desire to secure by Letters Patent, is—

1. A stocking-supporter having at its upper end a two-part suspension-tab adapted to embrace the lower edge of the corset or other garment of the wearer.

2. A stocking-supporter having at its upper end a two-part suspension-tab of loosely-woven or reticulated material adapted to embrace the lower edge of the corset or other garment of the wearer.

In witness whereof I have hereunto subscribed my name in the presence of two witnesses.

DE VER H. WARNER.
